UNITED STATES PATENT OFFICE.

ROBERT P. EBERHARD, OF MEADOW, VIRGINIA.

IRONING BOARD.

Application filed July 2, 1921. Serial No. 482,244.

To all whom it may concern:

Be it known that I, ROBERT P. EBERHARD, a citizen of the United States, residing at Meadow, in the county of Henrico and State 5 of Virginia, have invented new and useful Improvements in Ironing Boards, of which the following is a specification.

This invention relates to ironing boards, and comprehends a construction which can 10 be readily and easily clamped upon the edge of the table or other suitable support, for which purpose the supporting leg of the board is pivoted adjacent one end thereof and adapted to project above the board 15 through a slot opening at one end of the latter.

The chief characteristic of the present invention resides in equipping the board with a pair of pivoted members mounted 20 upon the board at the opposite sides of the slot, and designed to permit the board to be properly clamped upon tables or supports of different thicknesses, the invention residing in the construction, combination, and arrangement of parts as claimed.

In the drawings forming part of this application, like numerals of reference indicate similar parts in the several views and wherein:

30 Figure 1 is a side elevation of the board, showing the same supported upon the edge of a table or the like.

Figure 2 is a top plan view, showing the adjustable members in their normal position.

Figure 3 is a similar view, showing the adjusted position of said members.

Figure 4 is a bottom plan view of the board with the supporting leg in a folded 40 position.

Figure 5 is a detail view of one of the adjustable members.

Referring to the drawings in detail, 10 indicates an ironing board of well known construction having a slot 11 opening at one end of the board. Secured to the underside of the board and at opposite sides of the slot 11 are cleats 12 between which the supporting leg 13 is pivoted.

50 When the leg is folded it is arranged against the underside of the board in parallelism therewith as clearly illustrated in Figure 4, but the leg is mounted in a manner so that one end of the leg can project through 55 the slot 11 above the upper face of the board,

so that the board can be clamped upon a table edge or other suitable support indicated at 14. For this purpose, the underside of the leg is equipped with a block 15 one side of which is provided with corrugations 16 to 60 prevent the upper surface of the table or support 14 from being marred as will be readily understood. The upper end of the leg supports a plate 17 which is covered with asbestos 18, this plate constituting a sad 65 iron support.

Pivoted upon the upper surface of the board 10 at the opposed sides of the slot 11, are blocks 19 of the construction illustrated in Figure 5. These blocks are reduced at one 70 end to provide shoulders 20 arranged transversely of the block. The blocks are pivoted at a point between their ends as at 21, so that the blocks can be arranged transversely of the board, or in parallel relation 75 with the slot 11 as the occasion may require. When the board is used in conjunction with a table edge or support 14 of proper thickness so that the gripping surface of the leg may be properly presented to the upper surface of the support, the blocks 19 are arranged 80 transversely of the board 10, in which position the corresponding longitudinal edges of the blocks constitute stops 22 which bear against the adjacent edge of the support 14 85 when the board is positioned for use. However, when the board is used in connection with a table edge or support of less thickness, the blocks 19 are swung upon their pivots to lie parallel with the slot 11, with the reduced portions of the blocks arranged to lie beneath the table edge or support 14. When in this position, the shoulders 20 formed on the blocks engage the adjacent edge of the support 14. 90

While it is believed that from the foregoing description the nature and advantages of the invention will be readily apparent, I desire to have it understood that I do not limit myself to what is herein shown and described, 100 and that such changes may be resorted to when desired as fall within the scope of what is claimed.

What I claim is:

An ironing board having a slot at one end 105 thereof, a supporting leg pivoted beneath the board and movable through the slot, a clamping block carried by the upper end of the leg, blocks reposing upon the board at opposite sides of the slot, each block hav- 110

ing a reduced portion defining a shoulder arranged across the transverse center of the block, said shoulder being recessed, said block having an opening beneath said recess, 5 pivots passed through said recesses and openings and connected with the board whereby said blocks are pivoted upon the

board, and adapted to be arranged transversely of the board in horizontal alinement, or parallel with said slot, with the reduced 10 portions outermost for the purpose specified.

In testimony whereof I affix my signature.

ROBERT P. EBERHARD.
